(57) **CLAIM**

The ornamental design for micro water feature inline adapter fitting with angled LED light port, as shown and described.

DESCRIPTION

FIG. 1 is an isometric first side view of the micro water feature inline adapter fitting with angled LED light port. FIG. 2 is a first side view of the micro water feature inline adapter fitting with angled LED light port.

FIG. 3 is a second side view of the micro water feature inline adapter fitting with angled LED light port.

FIG. 4 is a third side view of the micro water feature inline adapter fitting with angled LED light port.

FIG. 5 is a fourth side view of the micro water feature inline adapter fitting with angled LED light port.

FIG. 6 is a front (effluent) side view of the micro water feature inline adapter fitting with angled LED light port; and,

FIG. 7 is a back (influent) side view of the micro water feature inline adapter fitting with angled LED light port.

1 Claim, 7 Drawing Sheets
